(57) **CLAIM**

The ornamental design for a roof rack mount, as shown and described.

DESCRIPTION

FIG. 1 is a top-front perspective view of a roof rack mount, showing my new design in a used condition;
FIG. 2 is a detail top-front perspective view thereof;
FIG. 3 is a top plan view thereof;
FIG. 4 is a bottom plan view thereof;
FIG. 5 is a front elevation view thereof;
FIG. 6 is a rear elevation view thereof; and,
FIG. 7 is a right side elevation view thereof; with the left side elevation view being a mirror image thereof.
The broken lines shown in the drawings illustrate (1) portions of the roof rack mount, and (2) environmental structure of a vehicle, both of which form no part of the claimed design.
